UNITED STATES PATENT OFFICE

FRED E. NORTON, OF WORCESTER, MASSACHUSETTS, ASSIGNOR TO GENERAL ELECTRIC COMPANY, A CORPORATION OF NEW YORK.

COMPRESSOR.

1,197,653.

Specification of Letters Patent. Patented Sept. 12, 1916.

Application filed August 27, 1913. Serial No. 786,831.

To all whom it may concern:

Be it known that I, FRED E. NORTON, a citizen of the United States, residing at Worcester, county of Worcester, State of Massachusetts, have invented certain new and useful Improvements in Compressors, of which the following is a specification.

My invention relates to centrifugal compressors and the like, particularly compressors of this type which are intended to increase the pressure of a large volume of air or other elastic fluid to a moderate extent, and to the combination of a plurality of centrifugal compressor units in a multi-stage machine.

The object of my invention is to improve centrifugal compressors as regards both their action and their construction, and it comprises various novel features of operation and construction and various novel combinations and arrangements of parts.

I have hereinafter shown and described several machines constructed in accordance with my invention in which air or other fluid is compressed partly under the direct action of the rotary impeller and partly in suitable "nozzle" passages through which it passes after leaving the impeller, these machines being of the double-sided type and therefore practically self-balancing. It is to be understood, however, that while my invention extends to various specific features and details of the forms of embodiment hereinafter described, such features and details being of importance on account of their special advantages, yet the invention is not confined to these embodiments and their details, but can be otherwise carried out and applied.

Various advantages obtainable in connection with the invention will appear in the following description, while its scope will be indicated in my claims.

In the accompanying drawing Figure 1 is a view in vertical axial section through a single compressor unit in a plane taken on line 1-1 in Fig. 3 as seen from the right of said line, said section extending through the fluid inlet; Fig. 2 shows the machine in section in a plane taken on line 2-2 in Fig. 1 as seen from the right of this line, said section again extending through the inlet; Fig. 3 shows the machine in section through the impeller and the fluid discharge in a plane taken on line 3-3 in Fig. 1 as seen from

the left of this line, said section extending through the outlet; Fig. 4 shows the machine in section in a plane taken on line 4-4 in Fig. 3 as seen from the left of this line, said section again extending through the outlet; Fig. 5 is a side elevation illustrating a three-stage compressor constructed in accordance with my invention, certain parts being shown in section or broken away; Fig. 6 is a plan view of the same machine; and Fig. 7 is an end elevation, certain parts being shown in section or broken away.

As will be seen from Figs. 1, 2, 3 and 4, the double-sided rotary impeller 1 shown comprises two sets of vanes or blades 2 of general spiral or involute shape arranged about a hub 3 on opposite sides of a central disk or web 4 which merges gradually into the hub 3, the vanes of each set lying between the web 4 and an outside annular web or shrouding 5 of somewhat greater external diameter than the web 4, and the impeller as a whole being symmetrical with reference to the plane of the web 4. The vanes 2 and the webs 4 and 5 form a plurality of passages 6 extending both circumferentially and radially, and the air enters at each side of the impeller 1 centrally and in an axial direction through the annular opening 7 between the corresponding end of the hub 3 and the inner edge of the corresponding shrouding 5 and issues from the impeller peripherally in a number of streams. The vanes and passages 6 are so designed as to impart velocity to the air, and they may also and preferably do compress it to a certain extent. The direction of rotation of the impeller 1 being clockwise and the vanes 2 as shown extending counter-clockwise outward, the air is, as it were, left behind by the impeller 1; and though with reference to the impeller the streams of air are discharged backward and move counter-clockwise in an oblique or even tangential direction, yet absolutely they move clockwise, and the streams from each side of the impeller 1 immediately unite in an outwardly tending stream flowing in a clockwise direction which also in some degree temporarily merges with the similar stream from the other side. While this form of impeller with backward discharging vanes especially suitable for low pressure conditions forms

a part of my invention, yet it is not an essential feature thereof, since various other forms of impeller can be used in compressors constructed in accordance with the invention.

The impeller or rotor 1, it will be seen, is mounted on a shaft 8 and inclosed in a chamber 9 in a casing 10. The air is conducted or supplied to each of the inlet openings 7 of the impeller 1 through an inlet 11 extending up through the exterior wall of the casing 10 and through one of two duplicate approximately central inflow chambers or passages 12 which lie at opposite sides of the impeller chamber 9 and communicate directly with said inlet. As it leaves the impeller 1, the air moves outward in a clearance space in the chamber 9 around the impeller and gradually diminishes in velocity in consequence of the outwardly increasing area of this space. It is finally received and conducted away through circumferential annular discharge chambers or passages 13 that extend almost completely around the chambers 9 and 12 and through an outlet 14 more or less similar to the inlet 11. Except for these inlet and outlet openings 11 and 14 in its lower portion, the casing 10 is externally of a circular form, and its circumferential wall is concentric with the shaft 8, so that it differs quite markedly from centrifugal compressors or blowers as constructed prior to my invention. It is symmetrical; also, with reference to the plane of the central web 4 of the impeller 1, the portion on each side thereof roughly resembling a torus with a portion sliced off at that plane.

The impeller chamber 9, it will be seen, lies between two double partition walls 15 at opposite sides of the impeller 1, the annular space 16 between the walls at each side of the impeller serving for the circulation of water or other fluid whereby the interior of the compressor may be cooled to reduce the work of compression. The inflow chambers 12 lie between the walls 15 and the end walls 17 of the casing 10, and they open directly downward into the inlet 11 at opposite sides of the impeller chamber 9, and also communicate with said chamber 9 (see Fig. 1) through openings 18 in the walls 15 that register with the outer edges of the openings 7 of the impeller 1. The fluid passing out through the outflow or discharge chambers 13 is separated from that entering through the inflow chambers 12 by curved partition walls 19 which extend across between the partitions 15 and the end walls of the casing 10 and eccentrically around the openings 18. As will be seen from Fig. 2 the chambers 12 and the passage 11 are in consequence not arranged symmetrically with reference to the openings 18, but eccentrically in a sort of spiral or scroll, so that part of the fluid

passes up into each chamber 12 in a stream that tends to one side of its opening 18 and on around above and down to the other side of said opening; this has the two-fold effect of causing a uniform admission or flow of fluid through the opening 18 to the impeller 1 and of causing the fluid to pass to the vanes of the impeller with as little shock as possible.

The outflow chambers or passages 13 extend around between the spiral or scroll-like partitions 19 on the inside and the circumferential wall 20 of the casing 10 and a partition wall 21 (Figs. 1 and 3) which is in effect a prolongation of said wall 20 across the middle of the inlet 11 on the outside. Each of them communicates circumferentially and at one side with the circumferential clearance space of the impeller chamber 9 where the air begins to lose velocity between the rounded outer edges of the corresponding partition 15 and the opposite side of the V-shaped inwardly projecting ridge 22 at the intersection of the two torus surfaces of the wall 20. The sides and edges of the partitions 15 and the sides of the ridge 22 are preferably so designed that the circularly arranged or annular throats 23 between them constitute the chief means hereinbefore referred to as causing the slowing down and the further compression of the air after it leaves the impeller 1,—this effect being greater in them than in the outer clearance in the chamber 9.

As shown in Figs. 1 and 4, the throats 23 are most constricted at their entrances and thence gradually diverge until they merge in the outflow passage 13 proper, this wholly divergent form being best adapted for converting the velocity of the air from the impeller into a moderate pressure such as the machine illustrated is intended to produce. The throats 23 should, of course, be substantially uniform all the way around, both as regards width of entrance and variation in area beyond this point, since the air from the impeller 1 everywhere enters them in substantially the same quantity and with substantially the same velocity and pressure. At the outlet 14, where the ridge 22 does not exist, the sides and edges of the partition 15 should be designed so as to give a throat action equivalent to that of the two throats that exist elsewhere.

After the air from the two sides of the impeller 1 is divided by the ridge 22 and passes through the throats 23 into the outflow passages 13, it flows on around clockwise to the outlet 14, in two constantly growing streams, and the outflow passages 13, therefore, increase in area all the way around to accommodate the growth of the streams, and accordingly have a sort of spiral or scroll-like form the reverse of that of the inflow chambers 12. If they are de-

signed merely to accommodate the growing streams of air (for they may, if desired, be designed so that they shall also have a nozzle or throat action and give some additional conversion of velocity into pressure), the air will be conveyed by them to the outlet 14 with substantially the same velocity as it had on issuing from the throats 23,—which, for example, may be .50 feet per second as compared with 200 feet per second for the air as it leaves the impeller 1. As will be seen from Figs. 1, 2, 3 and 4, the increase in area of the passage 13 begins near the bottom of the chambers 9 and 13. From about the region 24 (Fig. 3) on around clockwise to about the region 25 (Figs. 2 and 3), the increase takes place principally by an endwise widening of the chambers 13, and thence on around to the outlet 14 it is largely or principally due to the turning inward of the partition 19. While the outer clearance space of the impeller chamber 9, the throats 23, and the outflow passages 13 are in the main successively traversed by the air and are functionally more or less different as above indicated, nevertheless it will be seen that in a sense they are all parts of one single annular outflow path or passage of gradually increasing area surrounding the impeller chamber 9 and the inflow chamber 12.

The inlet passage 11 and outlet passage 14 are separated from one another by a partition 26 (Fig. 2 and 3) that extends up from the bottom of the casing 10 where the separate inlet and outlet conduits 27 and 28 are secured to the latter and join the partition 21 at 29. The conduit 28, it will be seen, is smaller than the conduit 27, the difference corresponding more or less to the increase in pressure produced in the machine.

Referring, now, to the structural features of the machine, it will be observed that the casing 10 is made in lower and upper halves 30 and 31 which may be bolted or otherwise secured together, the lower half containing the inlet and outlet passages 11 and 14 and the upper half serving, as it were, as a cover. The end walls 17 are in part integral with the rest of the casing and in part consist of more or less nearly conical shaped pieces 32 (Figs. 1 and 4) bolted in circular openings in the portions of the end walls that are integral with the rest of the casing. The shaft 8 extends through one of these parts 32 and stops short at the other. The impeller 1 is keyed or otherwise secured against turning on a slightly reduced portion of the shaft 8 and held by a collar 33 screwed on its end. The interior partitions are for the most part integral with the lower and upper halves 30 and 31 of the casing; but the inner walls of the double walled partitions 15 are formed by separate annular parts 34 which fit between the

portions of the walls 15 which are in the lower and upper halves of the casing. As shown, each of these parts 34 has at its inner edge two grooves 35 (Fig. 1) which receive rings 36 on the inner edges of the shrouding 5 of the impeller 1, the object being to prevent or impede leakage of the fluid from the impeller back to the inflow chambers 12. These rings are shown as on a separate part 37 threaded or otherwise removably secured on the shrouding 5: this construction permits them to be made of copper or the like so that they will wear if they come in contact with the associated portions of the partitions 15 above described (as they are liable to do in consequence of temperature changes or distortions of the parts), and can easily be replaced when excessively worn.

The construction of the impeller casing 10 which I have described permits it to be made more compact and of smaller diameter than is possible with previous constructions, and also simplifies the patterns necessary for casting it and reduces the amount of metal required and consequently the weight. An important feature of the casing in the securing of these advantages is the spiral arrangement of the inflow and outflow chambers or passages 12 and 13 so that the increase in the cross-sectional area of the outflow chambers 13 is partly made by an increase in their extension endwise of the machine. The saving in outside diameter and in weight of metal may be as high as 25%, or, in some cases, even 50%, and the cost of manufacture is also considerably reduced. Needless to say, the symmetrical form of the casing 10 with reference to the impeller shaft 8 and to a plane transverse thereto greatly enhances the good appearance of the machine.

Referring now to Figs. 5, 6 and 7, I have indicated somewhat diagrammatically how my invention may be adapted and applied in connection with multistage machines. In the structure illustrated, there are three stages consisting of as many complete, separate units 41, 42 and 43 such as above described with their rotors on a common shaft 44. It will be seen that the inlet 45 of the left-hand unit 41 and the outlet 46 of the right-hand unit 43 are at the top instead of at the bottom. As shown, the upper halves of the casings of all these units are united in a single casting 47, and the lower halves likewise,—though the casings of the several units may also be made separate and bolted together, which construction has the advantage of allowing any number of intermediate stage units desired to be introduced between two suitable terminal stage units. The stages do not communicate directly within their casing, but are all mounted on a base 48 which has passages or conduits 49

connecting the outlet 50 of the first stage unit 41 with the inlet 51 of the intermediate stage unit 42 and the outlet 52 of the intermediate stage unit 42 with the inlet 53 of the last stage unit 43. From the base 48 walls 54 extend upward around the compressor units and form a tank inclosing them in which water or other cooling fluid may be circulated in any suitable manner,—

10 as by means of inlet and outlet pipes 55 and 56 and diaphragms 57 which cause the water to traverse the casings of the various stages and the submerged stage connections on its way from the inlet to the outlet.

15 In accordance with the provisions of the patent statutes, I have described the principle of operation of my invention, together with the apparatus which I now consider to represent the best embodiment thereof; but

20 I desire to have it understood that the apparatus shown is only illustrative, and that the invention can be carried out by other means.

What I claim as new and desire to secure

25 by Letters Patent of the United States, is,—

1. A compressor comprising a rotary impeller and a circular casing therefor whose circumferential wall is concentric with the impeller, said casing having at one side of the impeller, a circumferential outflow passage which communicates sidewise and circumferentially therewith and which also communicates with an outlet from the casing and gradually increases in cross section 30 toward said outlet, and said casing also having at the side of the impeller an inflow chamber whose outer wall is formed by the inner wall of said outflow passage.

2. A compressor for elastic fluid comprising a rotary impeller and a casing in which said impeller is inclosed having a chamber for the impeller with an opening for admitting fluid sidewise into the impeller and also having therein an annular outflow passage 40 extending around said opening which at one side communicates circumferentially with the impeller through a throat adapted to convert the velocity of the fluid passing through it into pressure and which also 45 communicates with an outlet from the casing, said outflow passage gradually increasing in cross-sectional area toward said outlet.

3. A compressor for elastic fluid comprising a rotary impeller which imparts velocity 50 to the fluid and a circular casing in which said impeller is inclosed whose circumferential wall is concentric with the impeller, said casing having therein an inflow chamber for supplying fluid to the impeller and an outflow passage extending around said inflow chamber which receives fluid from the impeller through divergent nozzle means and communicates with an outlet from the casing, the cross-sectional area of said passage 55 gradually increasing toward said outlet.

4. A compressor comprising a rotary impeller and a circular casing whose circumferential wall is concentric with the impeller having therein a chamber in which said impeller is inclosed, an inflow chamber for supplying fluid centrally to the impeller which is itself eccentric with reference to the opening therefrom to the impeller, and an outflow chamber extending around said inflow chamber which communicates circumferentially with the chamber containing the impeller and which also communicates with an outlet from the casing, the cross-sectional area of said outflow chamber gradually increasing toward said outlet.

5. A compressor comprising a rotary impeller and a circular casing whose circumferential wall is concentric with the impeller having a chamber in which the impeller is inclosed with an opening for admitting fluid 85 sidewise into the impeller and an annular outflow passage for receiving fluid from the impeller with which said chamber containing the impeller communicates circumferentially, said outflow passage being separated from the fluid entering the impeller by a wall extending spirally about the opening into the impeller and communicating with an outlet from the casing toward which it gradually increases in cross-sectional area, the increase in cross-sectional area toward the outlet being in part due to increasing extension of the outflow chamber sidewise and in part to the spiral arrangement of the wall aforesaid.

6. A compressor comprising a rotary impeller and a circular casing in which said impeller is inclosed whose circumferential wall is concentric with the impeller, said casing having inlet and outlet openings adjacent one another and also having at one side of the impeller reversed spiral inflow and outflow passages or chambers communicating respectively with said inlet and with said outlet, the former of which supplies fluid centrally to the impeller while the latter extends around the former and receives fluid from the impeller through a divergent annular throat, said outflow passage or chamber gradually increasing in cross-sectional area toward said outlet.

7. A compressor comprising a rotary impeller and a circular casing whose circumferential wall is concentric with the impeller having therein a chamber in which said impeller is inclosed, an inflow chamber at either side of said impeller chamber with an opening for the supply of fluid to the impeller, and outflow passages for receiving fluid from the impeller extending around 125 said inflow chambers and separated from the latter by walls which extend eccentrically about the openings to the impeller, said outflow passages communicating with an outlet from the casing at 1 gradually in-

- creasing in cross-sectional area toward said outlet.
8. A compressor comprising a rotary impeller which acts to impart velocity to the fluid to be compressed and discharges it in two streams and a circular casing for the impeller whose circumferential wall is concentric therewith having therein at opposite sides of the impeller annular circumferential 10 outflow passages for receiving said streams and conveying the fluid from the casing, the communication between the impeller and said passages being so shaped that as each stream passes from the impeller to the outflow passage which receives it its velocity is diminished and its pressure increased, and each of said passages gradually increasing in cross-sectional area toward the outlet by which the fluid passing through it leaves the 20 casing.
9. A compressor comprising a double-sided rotary impeller which acts to impart velocity to the fluid to be compressed and discharges it peripherally in two outwardly 25 tending streams and a circular casing whose circumferential wall is concentric with the impeller having therein a chamber in which said impeller is inclosed, reversed spiral inflow and outflow passages or chambers at opposite sides of the impeller chamber the former of which supply fluid centrally to the corresponding sides of the impeller while the latter extend around the former and receive the streams of fluid from the corresponding sides of the impeller through divergent annular throats which extend outwardly and sidewise into them from the impeller chamber and act to diminish the velocity of the streams and increase their 35 pressure, said outflow passages or chambers communicating with an outlet from the casing and gradually increasing in cross-sectional area toward said outlet.
10. A compressor comprising a rotary im-
- 45 peller having vanes arranged to impart velocity to the fluid undergoing compression, a circular casing that surrounds the impeller whose circumferential wall is concentric with the axis thereof, walls at the sides of the impeller that coöperate with the casing 50 to form throats through which the fluid from the impeller flows in two streams, said throats acting to change velocity of the fluid into pressure, walls located on each side of the impeller and within the casing which co-operate with the casing wall to form chambers receiving fluid from the throats, said chambers enlarging from one end toward the other in an axial direction, a conduit receiving the fluid from both of said chambers, and means for admitting fluid to the 55 impeller.
11. A multi-stage rotary compressor comprising a plurality of compressor units having rotors which are mounted on a common 60 shaft, a casing for each unit, the circumferential wall of which is concentric with its rotor, said casing being formed in upper and lower halves and provided with admission and discharge openings, said admission 65 opening communicating with an inflow chamber for supplying fluid to both sides of the impeller, and said discharge opening communicating with a chamber which surrounds the inflow chamber and receives fluid 70 from the impeller, and a common base upon which said casings are supported, said base having therein passages for connecting the outlet of one unit with the inlet of the next 75 unit.
- 80 In witness whereof I have hereunto set my hand this twenty-third day of August, 1913.

FRED E. NORTON.
